(57) CLAIM

The ornamental design for a gun vise, as shown and described.

DESCRIPTION

FIG. 1 is a first perspective view of a gun vise;
FIG. 2 is a second perspective view thereof;
FIG. 3 is a back view thereof;
FIG. 4 is a front view thereof;
FIG. 5 is a top view thereof;
FIG. 6 is a bottom view thereof;
FIG. 7 is a side view thereof;
FIG. 8 is an opposite side view thereof;
FIG. 9 is a first perspective view of a gun vise in a folded and collapsed state;
FIG. 10 is a second perspective view thereof;
FIG. 11 is a back view thereof;
FIG. 12 is a front view thereof;
FIG. 13 is a top view thereof;
FIG. 14 is a bottom view thereof;
FIG. 15 is a side view thereof; and,
FIG. 16 is an opposite side view thereof.
The broken lines in the figures show portions of the gun vise that form no part of the claimed design.
